THERMO-THERAPEUTICAL METHOD
AND APPARATUS

Charles Robert Elliott, New York, N. Y.

Application March 28, 1931, Serial No. 526,071

7 Claims. (Cl. 128—401)

This invention relates to thermo-therapy and has for its object the provision of an improved method and apparatus for carrying out thermo-therapeutical treatments. More particularly, the 5 invention relates to thermo-therapeutical treatment of the body cavities, such as the vagina, rectal applications for treatment of the prostate gland and the like.

Practically all of the pathogenic bacteria which 10 cause disorders in the human system thrive best at body temperature. Variations of temperature above and below the same ordinarily tend to interfere with the vitality and growth of such bacteria. For certain hardy types of harmful 15 bacteria quite elevated temperatures are required to destroy them or to render them sufficiently innocuous. Heretofore, however, it has not been possible to use the desirable higher temperatures due to the resulting necrosis and burning of the 20 tissue.

I have found that if thermal applications are made in the manner hereinafter set forth temperatures materially higher than those heretofore safely utilizable can be applied and remarkable therapeutic results effected.

In the more specific aspects of the procedure, as applied to the vagina for illustration, a distensible bag of suitably conductive material is inserted into the vaginal tract, water or other 30 fluid at a moderate temperature is introduced into and circulated through the bag under sufficient pressure to cause such distension thereof as will bring it into intimate contact with the walls of the vagina, and while maintaining the contact, the temperature of the circulating fluid is gradually elevated over a suitable period of time until the desirably elevated temperature is attained.

In the accompanying drawings I have shown 40 an illustrative form of apparatus for carrying out the method of my invention.

In the drawings:

Fig. 1 is a front view of the apparatus;

Fig. 2 is a plan view with the top of the apparatus removed;

Fig. 3 is a vertical section taken along the line 3—3 of Fig. 2;

Fig. 4 is an illustration of a type of bag suitable for vaginal application; and

Fig. 5 is a wiring diagram.

Referring to the drawings, reference numeral 5 designates the outer casing of the apparatus comprising a panel board 6 (Fig. 1), which casing encloses a tank 7 (Figs. 2 and 3) for the water or other fluid treating medium. A supply

pipe 8 provided with a screw cover 9 extends from the top of the apparatus to the tank to permit the periodic filling thereof as required.

A discharge pump 11 and an intake pump 12 of the turbine or other suitable variety are provided within the tank 7 to cause circulation of the fluid through the circulatory system, to be hereinafter described, and it is desirable that both pumps be disposed a suitable distance below the top of the tank to assure their immersion 10 in the fluid. Reference numerals 13 and 14, respectively, designate the inlet and outlet of pump 11, and 15 and 16 the inlet and outlet, respectively, of pump 12. The discharge pump 11 feeds 15 the discharge branch of the system which comprises a pipe 17 leading from the pump and connecting with a conduit 18 provided in one end of a rectangular block 19, which conduit leads to a discharge nipple 21. In the return branch 20 of the system a return nipple 22 leads to a conduit 23 provided at the opposite end of the block 19 and this conduit is connected by means of a pipe 24 with the intake pump 12. The pumps are driven by a suitable electric motor 25 of either the variable or constant speed type as 25 desired and preferably provided with a fan 26 to keep the motor cool.

A heating element 27 of suitable heating capacity, and preferably of the well known wire-wound resistor type, is disposed within a waterproof compartment 28 in the tank 7. To permit regulation of the temperature of such heating element a rheostat 29 of any suitable and well known type is included in the heating element circuit. A sliding contact blade 31 operated by 30 a knob 32 is mounted on the panel board 6 and by selective contact of said blade with the metal studs 33 of the rheostat the desired resistance 35 may be thrown into the circuit, all in the well known manner. The temperature of the heated 40 fluid being discharged from the tank 7 is indicated by a thermometer 34 of any suitable type, the bulb of which projects into the fluid passing through the conduit 18, which thermometer is 45 externally visible through a window 35 provided in the panel board 6.

Pressure in the system is indicated by a pressure gauge 36 of any suitable type which may be mounted in the conduit 18 and so disposed that the dial 37 registers with an aperture provided 50 therefor in the panel board 6.

The prevailing level of the liquid in the tank 7 may be ascertained by the use of a liquid level indicator 38 connected with the tank 7 at the bottom thereof and operated simply by the hy-

drostatic balance. The communicating piping 39 between the tank and the liquid level glass 41 is preferably so disposed and extended that the glass is in close proximity to the panel board 6 5 so that it may be observed through the window 42 provided in the board.

In Fig. 4, I have shown one form of bag 43 which is very satisfactorily applicable in treatments of the vagina. This bag consists of a casing 44 of rubber or other suitable distensible and waterproof material, which casing is formed with a collapsible wing or lateral extension 45, a similar collapsible opposite wing or lateral extension 46 and a neck 47. A stopper 48 is fitted tightly 10 into the neck 47 and carries inlet and outlet pipes 49 constructed of hard rubber or other suitable material and provided with nipples 51, over which are fitted the rubber tubes 52 and 53 which connect respectively with the discharge 15 and return nipples 21 and 22 of the pumping apparatus.

In order to regulate the distension of the bag produced by the pressure of the fluid circulating through the system and also to regulate the flow 25 of the circulating fluid either as an adjunct to or in the absence of variable speed in the motor 25, a valve 54 is provided in the conduit 18 of the discharge branch of the system, and a similar valve 55 is disposed in the conduit 23 of the return branch of the system. For this purpose any suitable type of valve may be used and in the illustration shown each valve consists of a rotatable, frusto-conical plug 56 provided with a transverse duct 57 for the passage of the fluid through 30 the plug. The valve is snugly fitted in a frusto-conical seat formed in the block 19 and a spring 35 58 is interposed between a washer 59 and a flanged head 61 on the plug to aid in maintaining the same in position so that the duct 57 will at all 40 times be disposed within the conduit. The opposite end of the valve connects with a knurl or valve control 62 mounted on the panel board 6 externally of the casing 5.

Fig. 5 is a wiring diagram for the apparatus, 45 which is self-explanatory.

An illustrative manner of carrying out the therapeutic method of my invention utilizing the apparatus described is as follows:

The tank 7 is filled with water or other suitable 50 fluid and by means of the electric heater 27 the temperature thereof is elevated to a degree suitable for the initial application of the treatment medium to the vaginal cavity, for example, to 100-105° F. With the tubes 52 and 53 connected 55 with the bag 43 and respectively with the discharge and return nipples 21 and 22 of the apparatus, the bag while in collapsed condition is inserted into the vagina. The motor is then 60 strated to operate the pumps and cause a circulation of water through the system with the valves 54 and 55 in a fully open position.

The flow of water into and through the bag 43 will cause some slight initial distension of the same and when the circulation is functioning 65 properly the valve 55 is then regulated to gradually restrict the flow of water through the return branch of the system until sufficient back-pressure has been built up to produce the desired 70 distension of the bag within the vagina. No matter what the position of the wings 45, 46 may be when the collapsed bag is inserted into the canal, upon distension they will assume their proper position therewithin.

The extent to which the internal pressure in 75 the bag should be built up, should be such that

the resulting distension of the bag will smooth out the folds of the vaginal canal to a suitable extent and bring the bag in quite intimate contact with the membrane of the vagina. In utilizing the distension for this purpose, however, care should be taken that the pressure upon protruding portions of the tissue should not be so excessive that the blood will be pressed out of the tissue, with the possibility of a local necrosis upon the subsequent elevation of the temperature. 10 This undesirable local pressure may be avoided by utilizing a bag which is constructed of suitably elastic material, for example very thin rubber, which will tend to expand into the depressions and conform with, rather than tend to flatten out, 15 protuberances which offer undue resistance.

In lieu of the pressure developing and circulation system noted, in which the pumps 11 and 12 are of the same capacity and the back pressure is built up by regulation of the valve 55, a discharge 20 pump 11 may be used which has a greater capacity than the intake pump 12, with the resultant provision of a normal pressure differential between the discharge and intake lines. If such an arrangement is utilized, at the commencement 25 of the operation the valve 54 should be closed to a suitable extent to prevent undue inflation of the bag 43 and thereafter opened as necessary to produce the distension desired, with appropriate regulation of the valve 55, if necessary.

The pressure registered by the pressure gauge 36 and the loss of water from the tank 7 indicated by the liquid level glass 41 will afford indicia of the distension produced and will aid in the instant and subsequent treatment of a patient.

When the desired distension has been obtained the water is then permitted to circulate through the bag for a short period of time at the moderate initial temperature, for example, 105° F., to 40 permit the vaginal region to become accustomed to that degree of heat. Thereafter the temperature is gradually elevated, an increase of three-quarters of a degree Fahrenheit per minute, providing in general a satisfactorily graduated increase. This temperature increase is obtained by suitable regulation of the temperature of the heating element 27 through the medium of the rheostat or otherwise with observation of the thermometer 34. If desired, a suitable automatic thermostatic control may be utilized.

By applying the dry heat in the manner noted in close contact with the membrane and with gradual elevation of the temperature, it is possible to attain without ill effect, temperatures 55 considerably higher than heretofore could be safely utilized and I have found that highly desirable therapeutic results are secured at the elevated temperatures obtainable. Temperatures as high as 140-145° F. have been attained 60 in a great many instances without detrimental effect or undue discomfort to the patient and with striking therapeutic effects. While such highly elevated temperatures are not always necessary, I have found that in general a temperature of not less than approximately 125° F. should be utilized.

One explanation which may be advanced with respect to the effect of the treatment is as follows: As the temperature of the region in contact with the bag is gradually elevated by the increasing temperature of the liquid circulating through the bag, the blood vessels in the vascular region gradually dilate. This dilation of the blood vessels is appreciably greater at the higher 75

temperatures than at the lower. With such dilation a greater quantity of blood will pass through the enlarged vessels and will serve to carry away the excess heat which otherwise 5 would cause considerable discomfort if mild, and necrosis or burning if unduly elevated. In addition, this "active" hyperemia quite probably contributes to the normalization of the tissue affected, for example by relieving congestion in 10 the tissue, by destruction or attenuation (or what might be called rendered comatose or non-virulent) of the bacteria, apart from the effect of the heat, or by some other action.

With respect to the heat and temperature 15 effect, the heat from the high temperature bag will tend to destroy or attenuate the bacteria which lie in contact therewith and within the effective penetration range in the tissue.

In addition to the heat effects, a distinct physical 20 reaction is produced in the blood stream due to the enlargement of the blood vessels, viz., the production of leukocytosis to such an extent that the number of leukocytes or enemies of bacteria in the blood is very greatly increased, for example, from 10 to 50 per cent in forty-five 25 minutes. With the increase in the number of leukocytes the destruction and attenuation of the bacteria will be greatly enhanced and furthermore as regards destruction, the same will be accomplished with relative ease in the case of the bacteria already weakened by attenuation as a result of the heat, etc.

Whatever the exact mechanics of the operation and the relative influences of the various elements noted may be, however, the fact remains 35 that by proceeding in accordance with the method noted and the attainment of elevated temperatures, the beneficial effects which result are very marked.

40 The application of the method and apparatus of my invention just described is intended merely to be illustrative and various changes in and other applications of the same may be made as will be apparent to one skilled in the art. Their 45 application is not, for example, limited to treatment of the vagina, but may also be applied to treatment of the rectum, the nasal and aural cavities, etc. In the treatment of such cavities, of course, the bags utilized should be of such construction as to conform to those cavities. Likewise, the method and apparatus may be utilized 50 to apply a gradually decreasing degree of temperature where the beneficial effect of low temperatures is sought.

55 I claim:

1. The method of applying thermo-therapeutical treatments which comprises, disposing a heat-transmitting inflatable container within a body cavity, inflating said container to bring it 60 into intimate contact with the walls of said cavity, circulating a fluid through said container while maintaining said inflation, and progressively elevating the temperature of said fluid at a rate not substantially exceeding approximately 65 three-quarters of a degree F. per minute.

2. The method of applying thermo-therapeutical treatments which comprises, disposing a heat-transmitting inflatable container within a body cavity, inflating said container to bring it 70 into intimate contact with the walls of said cavity, circulating a fluid through said container while maintaining said inflation, progressively

elevating the temperature of said fluid at such a degree of gradation that necrosis of the tissue is avoided, and continuing said progressive elevation until a temperature of not less than approximately 125° F. is obtained. 5

3. The method of applying thermo-therapeutical treatments which comprises, disposing a heat-transmitting inflatable container within a body cavity, inflating said container to bring it into intimate contact with the walls of said cavity, circulating a fluid through said container while maintaining said inflation, progressively elevating the temperature of said fluid at a rate not substantially exceeding approximately three-quarters of a degree F. per minute, and continuing said progressive elevation until a temperature of not less than approximately 125° F. is obtained. 10

4. The method of applying thermo-therapeutical treatments which comprises, disposing a heat-transmitting inflatable container within a body cavity, inflating said container to bring it into intimate contact with the walls of said cavity, circulating fluid through said container under suitable pressure to maintain said inflated contact, progressively elevating the temperature of said fluid at a rate not substantially exceeding approximately three-quarters of a degree F. per minute, and continuing said progressive elevation until a temperature of not less than approximately 125° F. is obtained. 15

5. The method of applying thermo-therapeutical treatments which comprises, circulating fluid in non-contacting heat-transmitting relationship to the walls of a body cavity, said fluid 20 having an initial temperature of approximately 100 to 105° F., progressively elevating the temperature of said fluid at a rate not substantially exceeding approximately three-quarters of a degree F. per minute, and continuing said progressive elevation until a temperature of not less than 25 approximately 125° F. is obtained. 30

6. The thermo-therapeutical apparatus which comprises, an inflatable bag adapted to be disposed within a body cavity, pump means for circulating fluid through said bag, heating means for gradually elevating the temperature of the fluid, and means for providing a pressure differential between the stream of liquid supplied to said bag and the stream of liquid discharged 35 from said bag whereby said bag will be distended. 40

7. In a thermo-therapeutical apparatus of the class described, a casing, a fluid container therein, a heating element in the container, means for varying the heat produced by said heating element, a pump for discharging fluid from said container, a pump for drawing fluid into said container, a source of power having a common driving connection with both said pumps, a header having a bore extending partially thereto from one end, said bore being connected to the discharge from said container and a bore extending partially thereinto from the other end, said second bore being connected to the intake pump, said respective bores having respective 50 connections for discharging the fluid to and withdrawing it from an external apparatus, and means in the discharge end of the header for varying the rate of flow of the discharged fluid and means in the other end for varying the rate 55 of flow of the indrawn fluid. 60

CHARLES ROBERT ELLIOTT.
